UNITED STATES PATENT OFFICE.

FRANK WALTHER EDUARD WEISSE, OF CUERO, TEXAS.

DESIGN FOR A RADIOCABINET.

Application filed December 4, 1922. Serial No. 4,486. Term of patent 3½ years.

To all whom it may concern:

Be it known that I, FRANK WALTHER EDUARD WEISSE, a citizen of the Republic of Germany, residing at Cuero, in the county of De Witt and State of Texas, have invented a new, original, and ornamental Design for Radiocabinet, of which the following is a specification, reference being had

to the accompanying drawing, forming part thereof.

The figure is a perspective view of my radio cabinet, showing my new design.

I claim:

The ornamental design for a radio cabinet, as shown.

FRANK WALTHER EDUARD WEISSE.
